Henry C. Jones

These Selectmen referred to an abstract of others Patent and made
affidavit of the same containing a description in the words of their
own Country. The May town of his then government in Woburn
Massachusetts

20
Hence all men by these Presents
That I being the Mayor of the City of Boston in the County of Suffolk,
& by command of the Magistrates for Boston, have made a new Wharf
planted to use, or most useful improvement in the mode of constructing walls
having in deep water not known or used before this my invention had
discovered & the principles thereof made publick. I have also
placed its application with the manner of using the same as fol-
lows to wit. 1st. I am in the usual way of laying a row
over a row of piles, each pile being driven at a suitable distance
from the other upon one side of the space on which the wall is to be
erected or the roadway over. 2nd. I am to provide another or
second row of piles each one of which being driven on the other side of
the space of paving but opposite to the last row, so as to be parallel to the first
row or line of piles. 3rd. That two rows or lines of piles being placed across
a roadway on the two sides of said space opposite to parallel to each
other, I am then to lay them in their proper positions by driving
each pile diagonally to every pile on any side in the row
opposite, driving & running them in the same side of the piles & placing
the other end of the same at a suitable distance from the first pile
and so every other pile they being fastened by like a suitable distance
the top of the piles to the same on the other side of the said
paving being ready of use over a row of piles known & used as
pavement. 4th. I am to lay upon the top of the same by my communication
a communication of paving stones & to lay them upon the same upon
one of said two rows of piles as above, and of such stones as the said paving

two land caps, or parallel lines of said. 5th I construct a frame of
 suitable form, upon materials containing windlass with their
 shaft, big wheels, frames & supports of platform for the workmen
 who may be employed to work the apparatus & machinery.
 6th I place the frame with its machinery & apparatus upon the caps
 made of timber so that the said frame with its machinery & apparatus
 may be moved backwards & forwards, or along & upwards & downwards as
 occasion may require. The platforms or supports for the workmen & the
 purchase or arms & wheels of the windlass being placed on the outside
 sides or extremities before the said two parallel lines of piles, & the other parts of
 said machinery & apparatus being placed between the two rows of piles aforesaid.
 7th I construct a platform of transverse & longitudinal timbers of
 sufficient strength & dimensions placing the longitudinal timbers upon
 the transverse ones at right angles with them within about four inches
 of the ends of the same, & fasten them together with treenails or in any other
 suitable way, the length of the transverse timber being about equal to
 the width of the space to be filled up between the rows of piles aforesaid;
 & the longitudinal timbers extending as far as may be necessary for the con-
 struction of any section of the wall or masonry to be built, against the
 ends of said longitudinal timbers, I fasten planks ^{or} planks ^{or} puncheons ^{or} logs ^{or} with
 spikes which are as guides in its passage downwards for the second section
 of the wall or masonry to be built. in 8th This platform I place be-
 tween the two rows of piles & beneath the windlass frame & in such a man-
 ner that the transverse timbers shall be a croft over the space to be built upon,
 while the longitudinal timbers extend along the said space in lines par-
 allel to the two rows of piles aforesaid & here over the water of said space, be-
 tween said rows of piles I sustain the aforesaid platform by means of
 ropes or strings, the loops of which being placed around the under side of the
 ends of said transverse timbers, while the other ends of said ropes or strings
 are fastened to the blocks belonging to the windlass aforesaid.
 9th The platform of transverse & longitudinal timbers being thus made
 placed & firmly laid over the space to be filled up or when the said
 masonry is to be constructed between the two parallel lines or rows of

platform as aforesaid. I place a provisional platform alternate courses of timbers in the form of headers & stretchers with a setting between them the first course of headers being resting upon the longitudinal timbers described with the transverse timbers of the platform & the first course of stretchers resting upon the ends of the headers directly over to the longitudinal timbers, the second & remaining courses of headers & stretchers resting upon each other over the former courses & that interstices are left between the timbers which after the platform has been lowered into its place are filled with rubble or large stones & as fast as the rubble propagates I lower the same into the water by the means of the windlass & apparatus of aforesaid & this I continue to do until the platform rests on the bottom & the wall rises as high as low water mark & then the ropes or slings are drawn off of the ends of the transverse timbers by means of tripping ropes connected with said ropes or slings for the purpose of the remaining or upper part of the wall is finished in the usual or any convenient way. 10th One section of the said wall being thus completed, I move the windlass frame with its apparatus along the side rails until it comes to the end of the platform & section of wall above as before, & proceed to construct, place & sustain another platform of transverse & longitudinal timbers as aforesaid, & this also is finished with alternate courses of headers and stretchers as aforesaid, I lower this second platform down in the manner above described until its sinks to the bottom of said space to be filled up, the planks at the end of the first platform serving as a guide for the second, & those of the second as a guide for the third & so on. And in this manner I construct platform after platform & section after section, until the entire wall or masonry upon the space between the two ends of piles of ground shall be one complete. It is to be noted that the windlass frame, platform of transverse & longitudinal timbers with the other machinery, apparatus & fixtures aforesaid must be carried in number & dimensions according to the nature & extent of the space on which the wall or masonry is to be constructed. The description above given may perhaps be better understood by reference to the following diagram & the explanation of figures which is as follows to wit: Fig. 1 exhibits an end view of

the two rows of piles, the central platform being supported by a long transverse platform, A. A. The rows of piles being placed within the space between which the wall is to be built, with a space sufficient to allow the platform, B, to pass down between them, constructed, B, a platform upon piles on the external side of the piles A, A, which serve to strengthen and support them. C, C. The arms to the two rows of piles A, A, on which the frame D, is made to move forward & backward as occasion may require. D, is the frame of the principal machinery, & is composed of two internal longitudinal sills A, A, one front transverse sill y, y, y, y, mutually connected together by mortises & tenons & two external upper longitudinal beams b, b, resting upon the tops of the posts c, c, c, c, & secured to them by mortises & tenons & the posts c, c, c, c, rest upon the outerward longitudinal sills A, A, perpendicular & are secured to them by mortises & tenons y, y, one transverse & two resting on the tops of the posts c, c, c, c, & mortised & tenoned at their ends into the longitudinal beams b, b, & the frame D, may be varied in its dimensions & in the number of its sills, beams & posts according to the dimensions of the wall to be constructed & other circumstances. E, E, are common windlasses having journals at each of their extremities which revolve in boxes affixed to post c, c, c. The outward ends of said windlasses have attached upon their journals a shaft & cog wheel of proper size which are set upon & turned by the tooth of pinions fixed upon the ends of the shafts of the arms or purchase wheels P, P, which shafts revolving in proper bearings affixed to the posts c, c, c, have upon their opposite ends a set of purchase arms by which the workmen move the machinery. Two four purchase or arms wheel D, D, D, D, on each side of frame D, but every other one of the series is attached to a shaft the end of which extends beyond the outward end of the frame D, a sufficient distance, not to interfere in their movement with each other & to allow the workmen to pass forward & backward on a support or platform of planks on the space between the purchase wheels nearest to the frame D, and thus facilitate for it. The number of the wheel & shafts with the gearing and arrangement of the machinery varies with the same purpose & intention of the plant to support & extending along the

1118X

all ready giving of hand when a man is made use of to lay the
longitudinal timber 11 perpendicular to them, which is as against to the
construction of the wall or masonry to be built. Having thus being
done, I place or arranged timber before described. Then I lay
masonry as follows to wit, I place a course of headers 3.0.8.5
so that they may overlap the longitudinal timber 11 of the platform
to exactly on the transverse timber 1. 2. 3. 4. of the same platform. I then
place a course of stretchers 6. 7. 8. so that they may rest upon the course of
headers 3.0.8.5. directly over the longitudinal timber 11. Then I place
another course of headers as before & then another course of stretchers. Each
row of headers & stretchers resting upon each other on the preceding course.
placing them in an equal manner that intakes are left between
them which intakes are after the platform is laid down into its
place, filled up with rubble or any other materials suitable for the purpose.
After which you get the platform 11 is lowered from time to time by
wheel placed on the support of a large wheel 11. 7. 7. or
& this is continued to lower till the platform 11. with the wall or masonry
of as above described is constructed upon it, down to the bottom
or floor its bed or bottom in the mud or clay. & the wall or masonry
makes as high as low water mark. I then detach the sling ropes
11 from the end of the transverse timber 11. by means of the trapping eyes
on end & move the frame D. with its machinery apparatus. & systematically
the caps C. C. till it is even with the quining planks R. R. & proceed
to construct another platform 11. as before described from the action
of the wall or masonry to be built, which I build & construct as before
described till the whole of the contemplated wall or masonry
is completed in height as far as low water mark. & afterwards I finish
in the usual manner. And although I may have herein described
machinery & parts of machinery which have been known and used by others
in my invention, yet I hereby distinctly & explicitly declare that what is
hereby claimed by me, as my invention is the mode herein before described
of constructing walls & masonry in a particular & the particular
arrangement of the machinery apparatus, a having for instance

139

yourself of accomplishing this same.

After testing that the prop-
er is a true specification of my said improvement in the mode
of constructing walls & masonry or concrete with the mechanical
contrivance & mode of operating the same as herein described, I have
hereunto set my hand this 10th day of July in the year of our Lord eight
hundred and eight.
